(57) **CLAIM**

The ornamental design for a securing tie, as shown and described.

DESCRIPTION

FIG. 1 is a perspective view of a securing tie;

FIG. 2 is top view thereof;

FIG. 3 is a bottom view thereof;

FIG. 4 is a right side view thereof;

FIG. 5 is a left side view thereof;

FIG. 6 is an enlarged front view thereof;

FIG. 7 is an enlarged rear view thereof; and,

FIG. 8 is a perspective view of a second embodiment of a securing tie shown in a secured position. In FIG. 8, embodiment 2, the securing tie is shown with a symbolic break along its length. The appearance of any portion of the article between the break lines forms no part of the claimed design.
